Inventor:
Edward Van Camp.

UNITED STATES PATENT OFFICE.

EDWARD VAN CAMP, OF READINGTON, NEW JERSEY.

IMPROVEMENT IN HILLSIDE-PLOWS.

Specification forming part of Letters Patent No. 23,964, dated May 10, 1859.

To all whom it may concern:

Be it known that I, EDWARD VAN CAMP, of Readington, in the county of Hunterdon and State of New Jersey, have invented certain new and useful Improvements in Hillside-Plows; and I do hereby declare the following to be a full, clear, and exact description of the construction and operation of the same, reference being had to the accompanying drawings, making a part of this specification, in which—

Figure 1 represents a perspective view of the plow. Fig. 2 represents a vertical longitudinal section through the beam and parts beneath it. Figs. 3, 4, 5 represent detached parts of the plow.

Similar letters of reference, where they occur in the separate figures, denote like parts of the plow in all the drawings.

Hillside-plows have been made to turn under the beam on a vertical pin, or in a plane parallel to the plane of the beam; and they have been made with the double mold-boards cast in one piece, and also with the share in one piece. I do not claim any of these things regardless of the general construction of the plow; but the nature of my invention consists in casting or otherwise making the share, landside, and landside-brace of hillside-plows in one piece and of the form substantially with that shown in the drawings.

To enable others skilled in the art to make and use my invention, I will proceed to describe the same with reference to the drawings.

A represents the beam of the plow, and B B the handles. To the beam A is pivoted by a king-bolt, a, an under beam C, to which the mold-boards D D are united by means of the screw-bolts b b and c c.

E is the share of the plow. It is cast in one piece, with an opening through it, as seen more particularly in Fig. 4, to allow the dirt that gets behind the mold-boards to drop through. The sole of the share is of peculiar form, it being depressed in the center, so that whichever point is foremost the other one will not drag, but be raised above the active one. This share is held to the mold-boards and to the beam C by the screw bolts or rods b b, and other connections—such as projections and recesses—may be used, if necessary.

F is the landside. It may be made of a steel plate, with two cutting ends slightly curved to form colters. G is a landside-brace. Its two ends are so made as to lie snugly against the mold-boards, and it has projections d d thereon, through holes in which the rods b b pass and hold it firmly to the beam. The landside F is held to the landside-brace G by a screw-bolt, e. Both the landside and landside-brace are made in one piece.

The beam C is pivoted, as above described, to the main plow-beam A by the bolt a, so that the main beam may readily turn around in a horizontal plane on the under beam, C; but to keep it from turning when plowing the furrow, I arrange as follows: In each end of the beam C there is a vertical notch or gain, and in the main beam A there is hung a lock or latch, f, pivoted at g and controlled by a spring, h. To the top of this lock or latch is attached one end of a rod, cord, or chain, i, the other end of which extends into convenient position for the operator to catch hold of. When the main beam is to be turned on the under one it is only necessary to pull the rod, cord, &c., release the latch, and turn it round, and when reversed end for end the spring h throws the latch into the other slot or gain, and the two parts are again locked together. The approaching rear points of the mold-boards may be united by a separate piece, as seen at k. They are more readily cast in two pieces.

Having thus fully described the nature and object of my invention, I would state that I am aware many hillside-plows have been made which turn around as mine does. This I do not claim; but

What I do claim is—

Making the share, the landside, and the landside-brace of hillside-plows each in one piece and uniting them together to the mold-boards and beam in the manner and for the purpose set forth, thus making a cheap, strong, and efficient plow for hillside-plowing.

EDWARD VAN CAMP.
